(57) CLAIM

The ornamental design for a light fixture, as shown and described.

DESCRIPTION

FIG. 1 is a perspective view of a light fixture in accordance with the present design;

FIG. 2 is a front view thereof;

FIG. 3 is a right side view thereof, wherein a left side view is the mirror image thereof;

FIG. 4 is a top view thereof; and,

FIG. 5 is a bottom view thereof.

The broken lines in the drawings illustrate portions of the light fixture that form no part of the claimed design.
